UNITED STATES PATENT OFFICE.

FREDERICK C. OVERBURY, OF HILLSDALE, NEW JERSEY, ASSIGNOR TO THE FLINT-KOTE COMPANY, OF BOSTON, MASSACHUSETTS, A CORPORATION OF MASSACHUSETTS.

ROOF AND ROOF COVERING.

Application filed April 13, 1918. Serial No. 228,467.

To all whom it may concern:

Be it known that I, FREDERICK C. OVERBURY, a citizen of the United States, residing at Hillsdale, in the county of Bergen and 5 State of New Jersey, have invented new and useful Improvements in Roofs and Roof Coverings, of which the following is a specification.

This invention has relation to roofs and 10 roofing material, and it has for its object to provide certain improvements therein as will be hereinafter set forth.

Owing to the growing scarcity of wooden shingles and the danger of fire where they 15 are used, for some years there has been a marked increase in the use of roofing material fabricated of asphalt-saturated and coated felt. Such material has been supplied in sheet form, and also as shingle 20 strips or slabs and individual shingles, and has been rendered fire-resistant by an exterior layer of grit embedded in the layer or coating of asphalt. The use of the grit in different colors has permitted the attainment 25 of ornamental effects and has resulted in the employment of such roofing materials on high grade residences and other structures. In addition to such roofings, which are flexible by reason of the materials in- 30 cident to their construction, there have been placed on the market individual shingles or tiles consisting of molded material such as a mixture of asbestos or other fiber and a solidifying body of the character of Port- 35 land cement or concrete.

In all of these instances, the various roofing elements or units have required the employment of a continuous supporting surface such as afforded by a layer of boards 40 secured upon the supporting timbers or rafters. The object of this invention is to obviate the necessity of providing such a continuous support, by providing roofing elements of such inherent rigidity that they 45 may be secured directly to the rafters or timbers without the intervention of boarding, and to fabricate said elements in such

wise and of such rust-proof materials that they present, when laid, the appearance of individual shingles or tiles. These units 50 readily lend themselves to ornamentation, as will be subsequently explained.

To accomplish these objects, the invention consists of elongated rigid slabs of the desired thickness, preferably cast or molded 55 of non-metallic material of the nature of concrete, with which asbestos fiber, and coloring matter of desired, is thoroughly incorporated before the casting or molding operation. These slabs are preferably of 60 such length that they are capable of bridging adjacent rafters and of being secured directly thereon, and of such width that, when laid in overlapping horizontal rows in simulation of tiles or shingles, each slab overlaps portions of the slabs of two lower next 65 adjacent rows. To present the appearance of shingles or tiles when laid, these slabs are notched or serrated, as the case may be, or they are striped or ornamented according 70 to requirements. By providing the opposite ends of each slab with portions to interlock with compartmental portions on the ends of adjacent slabs, their alignment may be preserved, and each may be prevented from 75 dislocation in case of an imperfect fastening.

It is desirable that the elements or slabs of one row shall break joint with those of the contiguous rows, and therefore I preferably employ in the roof construction pairs 80 of timbers or supporting rafters, spaced apart a distance equal to half the width of one of the tabs or projections, or its equivalent of a slab. Thus the ends of the slabs of the alternating rows of slabs may be secured to the alternate rafters or timbers of each pair.

Referring to the accompanying drawings,—

Figure 1 represents a portion of a roof 90 structure embodying my invention.

Figure 2 illustrates one of the slabs formed with notches.

Figure 3 illustrates a slab which is striped

with material of a darker color to present the appearance of a notched slab.

Figure 4 shows a slab which is partially striped with short notches registering with 5 the stripes.

Figure 5 illustrates a slab having ornamental projections along one edge.

Figure 6 shows a slab which is serrated both at the bottom and top.

10 Figure 7 shows still another form of rigid slab.

Figure 8 represents a longitudinal section through several overlapping slabs and shows how they may be tapered from bottom to 15 top if desired.

I do not regard it as essential that any particular non-metallic ingredients should be employed in the fabrication of the slabs, so long as it is capable of being either cast or 20 molded and will set or solidify and furnish a rigid, substantially water-proof and weather-proof, rust-proof and non-corrodible slab. For example, I may employ a mixture of asbestos fiber and Portland 25 cement, or any suitable cementitious materials which chemically react, on being cast or molded, to produce the required result. The material preferably should be subjected to great pressure in the process of molding, 30 and it may have incorporated therein water-proof coloring matter. In fact, when forming the slabs in molds, there may be placed a thin layer of grit in the bottom thereof, so that the finished slab will possess an exterior rough layer of grit of the desired 35 color.

The several figures of the drawing, which illustrate different forms of slabs, require little explanation. In figure 2, the slab 40 10 is formed with notches 11, which provide a plurality of tabs 12 like the butts of shingles, along its lower edge, and at one end has the projections 13 and recesses or 45 sockets 14 to interlock with similar projections 15 and notches 16 on the opposite end of an adjacent slab. While I do not mean to be understood as limiting myself to any definite proportions, but as indicating the optimum dimensions for certain purposes, 50 I may say that the slab 10 may be 32 inches long, 16 inches in width, that the notches may be $\frac{1}{2}$ an inch in width and 7 inches long, and that each tab 12 may be $7\frac{1}{2}$ inches in width. The projections 13 and 15 should 55 extend beyond the end of the slab far enough to project entirely across the notches between it and the adjacent slabs and extend into the recesses 16 and 14 thereof.

In Figures 3 and 4, the dark colored 60 stripes 17 and 18 may be formed by small blocks of colored material previously mold-

ed, and then incorporated in the slab when it is formed.

In Figure 7, the lower portion of the slab is molded with a curved or waved surface to resemble curved tiles; and in Figure 8, the slabs are shown as tapering from bottom to top.

In building a roof, the roof timbers or rafters 20, 20, to receive and support the 70 slabs 10 of Figure 2, for example, may be spaced apart 30 inches from center to center, so that the slabs may have their abutting ends meet in the center of the timbers, and may bridge the space between said timbers, 75 as shown in Figure 1. The slabs are formed with one or more nail-holes at their ends, and preferably in the upper corners, through which the nails 19 are driven directly into the timbers. Supplemental or 80 additional timbers 21 alternate with those at 20, and are spaced apart far enough therefrom so that, when the next higher row of slabs are laid, the notches of one row of 85 slabs are midway between the notches 11 of the adjacent rows. For example, the main and supplemental timbers may be spaced $3\frac{1}{4}$ inches apart from center to center and secure the desired results.

A roof structure, such as described, is light 90 and inexpensive, and of course the same structure may be employed for the side walls of a building. I should not regard it as a departure from the invention if a layer of sheathing material were first laid upon the 95 rafters before the slabs were secured in place, or even if boards were laid below the slabs in certain cases where the slabs required reinforcement in strength.

Having thus explained the nature of my 100 said invention and described a way of making and using the same, although without attempting to set forth all of the forms in which it may be made or all of the modes of its use, what I claim is:

A roof or wall structure comprising elongated non-metallic rigid slabs laid in overlapping horizontal rows and adapted to simulate a plurality of spaced tiles or shingles, and two sets of parallel timbers supporting 110 said plates, the members of one set being arranged relatively close to the members of the other set and the members of each set being separated a distance slightly less than the length of the slabs and the meeting ends 115 of slabs in adjacent rows being attached to different sets of timbers, for the purpose described.

In testimony whereof I have affixed my signature.

FREDERICK C. OVERBURY.
